Inventor

UNITED STATES PATENT OFFICE.

WALTER HAROLD SMITH, OF NILES, OHIO, ASSIGNOR TO THE HARRIS AUTOMATIC PRESS COMPANY, OF NILES, OHIO, A CORPORATION OF OHIO.

PRINTING-PRESS.

No. 879,687.

Specification of Letters Patent.

Patented Feb. 18, 1908.

Application filed January 7, 1907. Serial No. 351,235.

To all whom it may concern:

Be it known that I, WALTER HAROLD SMITH, of Niles, in the county of Trumbull and State of Ohio, have invented certain new and useful Improvements in Printing-Presses; and I do hereby declare the following to be a full, clear, and exact description of the invention, such as will enable others skilled in the art to which it appertains to make and use the same.

The primary object of this invention is to provide simple and efficient means for automatically throwing the form-rolls of a printing press out of engagement with the form-cylinder, such means being ordinarily restrained by means which may be tripped either manually or automatically in the event of the throwing off of the press cylinders.

The invention will be hereinafter fully set forth and particularly pointed out in the claims.

In the accompanying drawings, Figure 1 is an end view, with some of the parts diagrammatically shown, and other parts omitted. Fig. 2 is a side elevation, with parts broken away. Figs. 3 and 4 are enlarged fragmentary views.

Referring to the drawings, 1 designates the series of form-rolls whose shafts are mounted in open top bearings 2. When the transfer-rolls 3 are raised, the form-rolls may be lifted from their bearings. The shaft of each form-roll carries, adjacent each end, a loose friction collar 4, with which are designed to engage shoulders 5 on the periphery of a plate 6 movable concentrically to the rolls, being mounted on an extension of the hub of the form-cylinder 7. Similar means is provided at each side of the press. The form-rolls 1 are arranged concentrically to the form-cylinder, as well as to plate 6, so that shoulders 5 upon engaging the collars 4 will lift the form-rolls from their bearings sufficiently to hold them out of contact with the form plate, and yet allow them to continue to rotate with the other ink-rolls.

The axial turning of the roll-lifting plate 6 may be accomplished by various means, but my invention contemplates the actuation of such plate by the recoil of a spring placed under tension by the lowering of the form-rolls into contact with the form-cylinder, that is to say, by the turning of plate 6.

This plate is shown as having an arm formed with a segmental rack 8 in mesh with a gear

9 on a shaft 10 extended across the press frame. On this shaft is a coil spring 12, one end of which is secured to the gear, and the other to the frame, such spring being placed under tension when the shaft 10 is turned to lower the form-rolls, the manipulating arm 13 of such shaft being then held by a trip 14 engaging a lug 15 projecting laterally from said arm. Said trip is in the form of a bell crank lever mounted on an extension of the press-frame, and is automatically disengaged from lug 15 by the downward movement of a trip rod 16 having a shoulder 16^a for engaging the end of the horizontal arm of such trip 14. The latter may be manually released by turning a handle 17 on the fulcrum shaft of such trip. The rod 16 is designed to be actuated to release the trip when the press-cylinders are thrown-off or out of printing relation. For this purpose I have shown the rod 16 connected at its lower end to the spring impelled shaft 18 to which the eccentric bearings of one of the press-cylinders, are connected. This may be the impression-cylinder, or it may be the transfer cylinder in a planographic or off-set press. Rod 16 is passed through a guide 19 and is normally held against the trip by spring 20, which latter yields sufficiently to allow the rod to clear the trip in its upward movement.

In practice, when the press-cylinder is tripped, by the actuation of the throw-off mechanism, with or without the actuation of stop mechanism, the rod 16 is pulled downwardly and its shoulder disengages trip 14 from lug 15 permitting shaft 10 to turn under the recoil of its spring, the gear 9 effecting, through its engagement with rack 7, the axial turning of the roll-shifting plate, thereby throwing the form-rolls out of engagement with the form-cylinder. This turning of the roll-shifting plate is assisted by the friction between such plate and the hub of the form-cylinder, which latter is revolved in the direction in which the shifting plate is moved by the spring. To restore the form-rolls to their normal working positions, the operator raises the arm 13 of the spring-impelled shaft until it is engaged and held by the trip, thereby putting the spring under tension ready, upon being released, to again actuate the roll-shifting plate.

I claim as my invention:

1. In a printing press, the combination

with the form-rolls, of means for moving such rolls out of their normal position, said means comprising a roll-engaging member, a spring-impelled shaft for actuating such member, a trip for normally restraining such shaft, and means for releasing such trip.

2. In a printing press, the combination with the form-rolls, and bearings therefor, of means for engaging such rolls and moving them from said bearings, said means comprising a roll-engaging member, a spring-impelled shaft for actuating such member, a trip for normally restraining such shaft, and means for releasing such trip.

15 3. In a printing press, the combination with a series of form-rolls arranged on the arc of a circle, of means for engaging said rolls and moving them out of their normal positions, comprising a roll engaging member movable concentrically to said rolls, a spring - impelled shaft for actuating such member, a trip for normally restraining such shaft, and means for releasing such trip.

4. In a printing press, the combination with a series of form-rolls arranged on the arc of a circle, of means for engaging said rolls and moving them out of their normal positions, comprising a plate mounted concentrically to said rolls and having a series 20 of peripheral shoulders for engaging the latter and moving them into a different plane, spring-impelled means for actuating such plate, and means for normally restraining such latter means.

35 5. In a printing press, the combination with a series of form-rolls arranged on the arc of a circle, of means for engaging said rolls and moving them out of their normal positions, comprising a plate mounted concentrically to said rolls and having a series 40 of peripheral shoulders for engaging the latter and moving them into a different plane, a spring - impelled shaft for actuating such plate, and means for normally restraining such shaft.

6. In a printing press, the combination with a series of form-rolls arranged on the arc of a circle, of means for engaging said rolls and moving them out of their normal positions, comprising a plate mounted concentrically to said rolls and having a series 50 of peripheral shoulders for engaging the latter and moving them into a different plane, a spring-impelled shaft for actuating such plate, a trip for normally restraining such shaft, and means for releasing said trip.

60 7. In a rotary printing press, having, in combination, a plurality of coöperating cylinders, and means for throwing such cylinders out of printing relation, a series of form-rolls arranged concentrically to the form-cylinder, a plate movable concentrically to said form-cylinder for moving said rolls out of contact with said form-cylinder, a shaft normally tending to actuate said plate, and

means designed to be actuated by the throw off of the press-cylinders, for permitting said shaft to actuate said plate to move said rolls out of contact with the form-cylinder.

8. In a rotary printing press, having, in combination, a plurality of coöperating cylinders, and means for throwing such cylinders out of printing relation, a series of form-rolls arranged concentrically to the form-cylinder, a plate movable concentrically to said form-cylinder for moving said rolls out of contact with said form-cylinder, a spring-impelled shaft for actuating said plate, a trip for normally restraining said shaft, and means for releasing said trip, such latter means being actuated by the actuation of the throw-off of the press cylinders.

9. In a rotary printing press, having, in combination, a plurality of coöperating cylinders, and means for throwing such cylinders out of printing relation, a series of form-rolls arranged concentrically to the form-cylinder, bearings for said form-rolls, and means for moving said rolls from their bearings in the event of the actuation of the throw-off of the press-cylinders, said means comprising a plate movable concentrically to said form-cylinder for engaging said rolls and moving them from their bearings, a spring-impelled shaft for actuating said plate, a trip for normally restraining said shaft, and a trip-rod for engaging said trip, said rod being connected to the throw-off mechanism of a press-cylinder.

10. The combination with the form-rolls having collars thereon, and bearings for said rolls, of an axially movable plate having peripheral shoulders for engaging said collars and moving said rolls from their bearings, means for actuating said plate, comprising a spring-impelled shaft, a trip for normally restraining said shaft, and means for releasing said trip.

11. The combination with the form-rolls, of the plate engaging therewith for moving said rolls out of their normal positions, said plate being movable concentrically to said rolls and having an arm equipped with a rack, a spring-impelled shaft having a pinion meshing with said rack, an arm on said shaft, a trip for engaging said arm, and means for releasing said trip.

12. In a printing press having a form-cylinder, and a series of form-rolls, means for automatically moving said rolls out of engagement with said form-cylinder, said means comprising a plate mounted concentrically to said form-cylinder and having peripheral shoulders for engaging said rolls, said plate having an arm carrying a rack, a spring-impelled shaft, a gear wheel thereon in mesh with said rack, an arm on said shaft having a lug, a trip for engaging said lug and holding said arm, a rod having a shoulder for engaging said trip, and a guide for said rod.

13. In a printing press having a form-cylinder, the combination of form-rolls, bearings therefor, a plate axially mounted on the hub of said form-cylinder, means for normally holding said plate as against turning with said form-cylinder, said plate being constructed to engage each of said rolls and move them out of their bearings, and means for releasing the holding means to permit 10 said plate to move with said form-cylinder to engage said rolls.

14. In a printing press having a form-cylinder, the combination of form-rolls, bearings therefor, a plate axially mounted on the 15 hub of said form-cylinder, and constructed to

engage said rolls and move them out of their bearings, said plate moving with said form-cylinder when actuated to engage said rolls, a segmental rack carried by said plate, a spring-impelled shaft, a gear wheel thereon 20 in mesh with said rack, a trip for normally restraining said shaft, and means for releasing such trip.

In testimony whereof, I have signed this specification in the presence of two subscribing witnesses.

WALTER HAROLD SMITH.
